UNITED STATES PATENT OFFICE

2,291,698

TEMPERATURE RESPONSIVE MEANS

Wilbur J. Crites, Bartlesville, Okla., assignor to
 Phillips Petroleum Company, a corporation of
 Delaware

Original application July 11, 1938, Serial No.
 218,659. Divided and this application June 8,
 1940, Serial No. 339,566

2 Claims. (CL 297-4)

This invention relates to the use of thermal expansion devices for the purpose of imparting motion. It often happens that the magnitude of the motion required is greater than the capacity of the actuating unit or if the unit is of sufficient capacity the space required is prohibitive, or the stability of the unit is such that it lacks the strength to directly operate the mechanism to which it is applied. The primary object of this invention is to afford a mechanism that is responsive to temperature changes in the translation of motion to a complementary mechanism in which the actuating mechanism occupied a minimum amount of space and imparts maximum motion and force to its complement.

This invention further relates to improvements in devices for automatically adjusting at the bottom of an oil well, or at some point below the ground surface, the flow of oil and gas, so that the well may be produced at a rate and/or in such a manner that the least amount of gas will be produced, or at a rate and/or in a manner that less gas will be produced than would be the case without this device. The device may be used to control the production of oil and/or gas coming from the producing formation, or it may be used to control the oil or the oil and gas coming from the producing formation activated by gas injected extraneously. The apparatus herein disclosed is an improvement over the apparatus shown in Patent 1,961,280 issued June 5, 1934, with the present inventor as a joint inventor thereof for carrying forward the same method disclosed in said patent, and is further a division of my co-pending application Serial No. 218,659, filed July 11, 1938, which issued as Patent No. 2,213,950 on September 10, 1940.

The invention further relates to improvements in devices for the recording of bottom hole temperatures or the range of variation in bottom hole temperatures in the bottom of a producing oil well.

A further object of the invention is to furnish the oil industry with a valve or choke, rugged in construction and positive and automatic in operation and adjustments, whereby the production of oil and gas may be so controlled that a greater amount of gas energy may be conserved in the producing formation than under customary producing methods, and possibly a greater amount than by any other method. The device may be applied to wells flowing under their own energy, to wells flowed by the introduction of extraneous gas, to wells in which the fluid is lifted by me-

chanical means, or to any combination of such lifting forces.

A still further object is to provide a device for the above-mentioned purposes, the adjustment and operation of which is effected by thermal control means, for example, through the expansion and contraction of confined liquids under changing temperatures.

In the production of any oil well, as the ratio of gas to oil increases, the temperature decreases; and conversely, as the ratio of gas to oil decreases, the temperature increases. Consequently, a device acting in response to temperature changes, we have discovered, may be used to control the flow so that the flow will be increased under increasing temperatures in the well, whereby the oil will be produced with less gas than if allowed to flow unrestricted or by a regulation that is unaffected by a gas-oil ratio influence.

It will therefore be understood that another object of our invention is to supply means for producing oil at low gas-oil ratios through the use of thermally operated devices responsive to changing temperatures coincident to changing gas-oil ratios whereby the thermally operated device is contacted by the liquid from the well before the fluid passes through the restricting valve or choke.

30 A still further object of the device is to use the same as a temperature recording mechanism to determine the variation of temperature existing in the well.

With the foregoing objects outlined and with 35 other objects in view which will appear as the description proceeds, the invention consists in the novel features hereinafter described in detail, illustrated in the accompanying drawing and more particularly pointed out in the appended claims.

In the drawing:

Figure 1 is a vertical sectional view illustrating the application of the device to be placed in an oil well,

45 Figure 2 is a side elevational view of the choke valve.

Figure 3 is a plan view showing the top of the choke valve.

50 Figure 4 is a side elevational view of one of the expansive members showing the approximate shape as derived from the collapsing of a sphere.

Figure 5 is a vertical sectional view illustrating the application of the device as a temperature recording mechanism.

55 Referring first to Figure 1, 1 indicates a string

of tubing to be placed within the casing lining a well bore and having a choke housing or case 2 attached on the end of the tubing. The housing 2 is lowered until it reaches the producing formation where the liquid from the well enters chamber 3 in the housing 2 through the perforations 4. The liquid from the well surrounds the expansion fluid containers 5 which are connected together by the rods 6 and the lowermost container is connected to the housing bottom through the rod 7. Rod 8 is connected to the upper most container which in turn connects to the flow choke 9.

The expansion fluid containers 5 are filled with mercury or any other fluid having a high coefficient of expansion and constructed as shown in Figure 4. The body of the containers is made from a light gauge metal and any metal possessing the requisite strength may be employed. The body is first made in the shape of a sphere as shown in dotted line and then pressed to the final shape, whereby the design of the thermal unit is arrived at by the collapse of a sphere to the point that the collapsing surfaces come in close contact with each other as indicated in Figure 4. Coupling members 10 and 11 for the connected rods are placed on top and bottom of the containers. The container is first filled with mercury before the top coupling member 11 is attached by welding or any other attaching means found suitable. A series of containers are then attached together by the rods 6 and 7 and connected to the flow choke 9 by means of rod 8. The flow choke seats on the valve seat 12 and has vanes 13 to guide the choke in its vertical movement.

In the operation of the choke, the liquid from the well flows into the chamber 3 through the perforations 4. The liquid surrounds the containers 5 and the mercury in the containers assumes the same temperature as the liquid and is likewise responsive to any change in temperature. The containers are so constructed that the valley portion 5-A thereof is the weakest portion of the container and the mercury in expanding or contracting, will exert its pressure at this point and cause the wall of the container to move upwardly or downwardly as the case may be. The container is shown in fully extended position in the solid lines of Figure 1 while the dotted lines show the container fully collapsed. As can be seen, the expansion and contraction of the members 5 may be translated into a vertical up and down movement. The vertical movement is transmitted from container to container 5 through the coupling means 6, rod 8 and finally to the choke member 9 where it acts either to seat or to lift the choke 9 from the seat 12. In this manner the oil from the well flows through the space between the valve seat 12 and choke 9 and the amount of oil flowing will be regulated by the extent of said opening. It is noted that in the present invention, the thermally responsive means 5 are contacted by the oil and gas flowing from the well before the oil and gas flow through the choke member and in this manner the thermally responsive means is contacted before the gas has had a chance to expand after passing through the choke means. Gas or oil passing through a restricted opening under pressure will have its pressure reduced after passing through the restricted opening because the gas and liquid will both be given a chance to expand. With the present arrangement, it can be seen that the temperature responsive means are placed

in such a position as to be affected by the true well condition before the gas has had a chance to expand after going through the choke and tends for more accurate choking of the flow.

As many containers 5 may be used as are necessary to get the required vertical movement to open or close the choke 9. The temperature differential will be slight so that small movement of each container can be expected so the movement of a number of them must be added together. In placing the device in a well it is first necessary to know the bottom hole temperature so that the containers 5 may be calibrated and number needed determined from the rate of production at which the well is to be flowed. Once the temperature of the well is known the containers 5 are placed in the choke housing 2 and subjected to the well temperature. It is then determined if the number of containers or expandable members 5 are sufficient to give the required space or opening between the valve seat 12 and choke 9 to give the production desired. If not, more containers or expandable members 5 are added. When once calibrated and ready for the well hole, the device is removed from the temperature bath. This will allow the mercury in the containers to contract which in turn will pull the choke 9 tightly onto the seat 12. However, it is contemplated placing the choke in the well immediately, so that little danger of the choke sticking on the valve seat 12 is present. As previously recited, as more and more gas appears with the oil, the temperature in the chamber 3 will be lowered which will tend to contract the mercury in expandable members 5 and thus close the choke 9. Again the important phase of the present disclosure is that the temperature responsive means is on the down side of the choke and not affected by any changes of temperature due to expansion of gas after it passes through the choke means.

Figure 5 shows the application of the vertical movement of expansion fluid containers to a recording temperature gauge to measure the variations of temperature which may exist in the bottom of a well. A case or housing 20 is shown which may be lowered into the well on a wire line attached to the eye 21. The bottom of the housing 20 has openings or slots 21-A which allow the fluid from the well to enter the housing. Mounted in the housing 20 and supported on the bottom thereof by means of rod 22 are the mercury filled expandable containers 23 which are of the same construction as previously described for the flow choke means. The expandable members 23 are connected together by means of coupling rods 24 as previously described and the operation and functioning of the expandable means is identical with that previously set forth for the flow choke. The uppermost expandable container 23 has the rod 25 mounted thereon and has the shaft 26 rotatably and longitudinally slidably therein. The rod 25 has mounted on its upper end a stylus 27 backed by a coil spring 28. In the upper end of the housing 20 is a clock mechanism 29 which may be of any known design to rotate the shaft 26. Mounted on the shaft 26 and rotatable therewith is the recording cylinder holder 30 which has a wax or soft metal lining 31 around the interior of the cylinder 30. The stylus 27 contacts the wax or soft metal on the cylinder and makes a recording thereon of any variation in temperature.

In the operation of the recording temperature gauge, it is first necessary to determine the bottom hole temperature by some known means in

order to calibrate the expansible containers 23. Once calibrated the device is lowered into the well with the clock mechanism 29 set in motion and the device allowed to remain in the well a requisite length of time. The clock mechanism will rotate the shaft 26 which in turn will rotate the cylinder 30 keyed thereto. The stylus 27 mounted on rod 25 will remain stationary and trace a line on the wax or metal coating 31 on the cylinder 30. Any change in temperature in the well will cause expansion and contraction in the expansible containers which in turn will be transmitted to the rod 25 as a vertical movement. This vertical movement up and down of the rod 25 will carry with it the stylus 27 which in turn will trace and record its movement on the wax or soft metal 31 on the cylinder 30. In this manner a true picture of the variations in temperature in the well bottom may be had from a study of the line traced on the coating 31. Knowing the coefficient of expansion of mercury and from previous calibration of the expansible containers, the degrees of change of temperature can easily be calculated.

From the foregoing it is believed that the construction, operation and advantages of our invention may be readily understood by those skilled in the art, and it is apparent that changes may be made in details disclosed, without departing from the spirit of the invention, as expressed in the claims.

What is claimed and desired to be secured by Letters Patent is:

1. Apparatus for use under external pressure for imparting linear movement in response to temperature changes comprising a self sustaining hermetically sealed fluid container of a flexible metal; said container having the shape resulting from the collapse of a sphere in one direction along a diametrical axis of the sphere, 40

the resulting container having a convex bottom with a radius of curvature greater than that of the original sphere, a concave top with a radius of curvature less than that of the bottom, a convex side wall joining the top with the bottom and having a radius of curvature less than that of the bottom; a substantially incompressible liquid filling said container, thermal volume changes of said liquid operating to move the top of said container relative to the bottom thereof; and means associated with the top of the container for transmitting linear movement to the member to be actuated.

2. Apparatus for use under external pressure for imparting linear movement in response to temperature changes comprising a housing; a plurality of self sustaining hermetically sealed fluid containers of flexible metal mounted in said housing, the lowermost container being rigidly secured to the bottom of the housing by a coupling member; each container having the shape resulting from the collapse of a sphere in one direction along a diametrical axis of the sphere, the resulting container having a convex bottom with a radius of curvature greater than that of the original sphere, a concave top with a radius of curvature less than that of the bottom, a convex side wall joining the top with the bottom and having a radius of curvature less than that of the bottom; a substantially incompressible liquid filling said containers, thermal volume changes of said liquid operating to move the top of said container relative to the bottom thereof; coupling means mounted between and on the tops and bottoms of the containers for transmitting movement from container to container; and a coupling means connected to the uppermost container for transmitting linear movement to the member to be actuated.
